UNITED STATES PATENT OFFICE.

E. NEILSON GAILLARD, OF NEW YORK, N. Y.

SPEAKING-TUBE.

SPECIFICATION forming part of Letters Patent No. 285,120, dated September 18, 1883.

Application filed February 20, 1883. (No model.)

To all whom it may concern:

Be it known that I, E. NEILSON GAILLARD, a citizen of the United States, residing in the city, county, and State of New York, have invented a new and useful Combined Call-Bell and Speaking-Tube, of which the following is a specification.

My invention relates to a combination of a speaking-tube and a bell or signal particularly designed for closed vehicles; and the invention consists, chiefly, in combining the mouth-piece of the speaking-tube with striking mechanism of a bell or other resonator, so that when the mouth-piece is drawn out in the same manner that a bell-pull is operated an alarm will be sounded to call the attention of the driver or other party whose attention is required, who can then be communicated with through the speaking-tube.

The mechanism of this invention is illustrated in the accompanying drawings, in which Figure 1 is a longitudinal sectional view, showing the speaking-tube, alarm-bell, and the mechanism for drawing back the mouth-piece and operating the hammer of the bell. Fig. 2 is a cross-section through line *e d*, Fig. 1.

Similar letters refer to similar parts throughout the different views.

X is the partition of a cab or other vehicle, to which the combined speaking-tube and alarm is attached, the mouth-piece *T* projecting inside, and the gong *G* is fastened upon the outside by means of the central tubular standard, *M*, provided with the flange *P*. The mouth-piece *T* has an extension, *N*, which slides inside the tube *M*. One end of the spring *W* is attached inside the mouth-piece at *g*, and the other end inside the extension of the tubular standard *M* at *h*, and by this spring *W* the sliding mouth-piece is drawn up to the partition *X*. Projecting through a slot in the tubular standard *M* is arranged the stud *H* in such a manner that it moves with the mouth-piece *T* when the latter is drawn away from the partition *X*, and is drawn back with it by the spring *W*. The stud *H* is so

adjusted in connection with the pivoted toe *L* and hammer *B*, which works on a pivot at *K*, that when the mouth-piece *T* is pulled, the stud *H* draws the bell-hammer *B* against the spring *Z* and strikes the bell, and when the mouth-piece *T* is released the spring *W* draws back the mouth-piece and its stud, the pivoted toe *L* allowing the stud *H* to pass by the end of the hammer *B*, and the spring *Z* presses the hammer back away from the bell. The extension of the tubular standard at *h* is arranged for the attachment of a flexible or other continuation of the speaking-tube, which may be of such form and length as to best adapt it to the position of the driver.

By this description it will be seen that a very compact and effective arrangement of speaking-tube and alarm is obtained by my invention, and that in use it is only necessary to use the mouth-piece of the speaking-tube as an ordinary bell-pull is used, and thus strike the alarm, after which the driver can be communicated with through the tube.

While this invention is especially adapted for use in covered vehicles, it may be used in other situations to which its construction adapts it.

Having described my invention, I claim—

1. In combination with a speaking-tube, the reciprocating mouth-piece and connecting mechanism and a bell or resonator for giving alarm by drawing out the mouth-piece, constructed and arranged as hereinbefore set forth.
2. The combination of the speaking-tube, the reciprocating mouth-piece *T*, the stud *H*, the tripping-toe *L*, and hammer *B*, and reacting spring *W*, forming the connection with the bell *G*, constructed and arranged as hereinbefore set forth.

In witness whereof I have hereunto subscribed my name and affixed my seal in the presence of two subscribing witnesses.

E. NEILSON GAILLARD. [L. S.]
